FOREIGN PATENT DOCUMENTS

JP D1511666 S 11/2014

Primary Examiner — Mitchell Siegel(74) Attorney, Agent, or Firm — Muncy, Geissler, Olds & Lowe, P.C.(57) CLAIM

The ornamental design for a wood golf club head, as shown and described.

DESCRIPTION

FIG. 1 is a perspective view of the wood golf club head showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a cross-sectional view taken along line 8-8 in FIG. 2.

The broken line showing is for the purpose of illustrating environmental structure and forms no part of the claimed the design.

1 Claim, 6 Drawing Sheets(56)
